UNITED STATES PATENT OFFICE.

MOSES C. SWEZEY, OF NEW HAVEN, CONNECTICUT.

CASH-CARRIER.

SPECIFICATION forming part of Letters Patent No. 398,356, dated February 19, 1889.

Application filed October 8, 1888. Serial No. 287,511. (No model.)

To all whom it may concern:

Be it known that I, MOSES C. SWEZEY, of New Haven, in the county of New Haven and State of Connecticut, have invented a new 5 Improvement in Cash - Railway Apparatus; and I do hereby declare the following, when taken in connection with accompanying drawings and the letters of reference marked thereon, to be a full, clear, and exact description of the same, and which said drawings constitute part of this specification, and represent, in—

Figure 1, a side view of a portion of the track of a cash-carrier apparatus, representing the 15 terminus with a car approaching; Fig. 2, a top or plan view of the same; Fig. 3, a transverse section through one of the wheels as running on the track; Fig. 4, a transverse section of the same wheel advanced onto the 20 expanded track; Fig. 5, a modification in the means for gradually increasing the transverse area of the track at the terminus or destination of the car.

This invention relates to an improvement 25 in that class of cash-carrier apparatus in which the track is a wire under sufficient tension to be held taut and straight and the car suspended from the wire, the grooved wheels of the car running upon the wire, and so that 30 a momentum imparted to the car from one point will be sufficient to carry it to its destination at the other point.

In the use of such apparatus the momentum 35 is frequently so great that a considerable force is required to stop the car at its destination.

Various appliances have been made to cushion or prevent the stop being too abrupt. These appliances are more or less complicated 40 and liable to derangement.

The object of my invention is to produce a resistance to the advance of the car beyond its destination which shall be easy, simple, and not liable to derangement; and it consists in the construction hereinafter described, 45 and particularly recited in the claim.

A represents the wire track, which is suspended in the usual manner and drawn taut.

B represents the car suspended from the 50 track and supported upon grooved wheels a a.

C represents the basket, which is removably attached to the car in the usual manner, and so that a slight force imparted to the car will cause it to travel upon the track toward its destination in either direction. This may 55 be imparted by any of the known means, the force to move the car constituting no part of my invention.

Near the point where the car is required to stop I gradually increase the diameter or 60 transverse area of the wire or track—say beginning at a point, b, and increasing therefrom to a point, d, near or slightly beyond the point where the car is required to stop, and so that as the car advances on the wire the wheels 65 will run onto the gradually-increasing diameter of the wire. This increase of diameter gradually fills the groove of the wheels, and consequently increases the friction between the surface on which the wheel rolls and the 70 wheel itself, the grooves of the wheels being considerably wider than the diameter of the wire A, so that running on the wire but a very slight extent of bearing is taken by the wheel, and consequently very little friction 75 during the running of the car over the wire of uniform diameter; but as the car advances onto this gradually-increasing size of the wire the filling of the groove causes the wheel to hug the wire more closely, as seen in 80 Fig. 4, and produce a rubbing effect thereon, which serves as a brake upon the advance of the car, and so that the advance of the car is easily retarded and quickly brought to a stand; but yet the car is readily thrown in the 85 reverse direction, so as to take it from the braking portion of the track and return it from whence it came.

The device which I have devised for so gradually increasing the size of the track is to 90 wind upon the track-wire, as represented in Fig. 1, there being other wire or filling of some character introduced between the outer convolutions and the wire, which will give to it the tapering or gradually-increasing diameter, as seen in Figs. 1 and 2. The gradually-increasing diameter may be readily produced, as represented in Fig. 5, by winding upon the wire several overlays of fine wire, the extent of each overlay gradually dimin- 95 100

ishing, so that practically a gradually-expanding track is produced.

I do not wish to be understood as claiming, broadly, a track for cash-carrier presenting a gradually-increasing transverse area on the approach to the stations, as such, I am aware, is not new.

I claim—

In a store-service apparatus, a track-wire

having near its termination a gradual enlargement formed by an overlay of wire wound thereon, said enlargement being adapted to gradually stop a car traveling on said track, all substantially as described.

MOSES C. SWEZENY.
